UNITED STATES PATENT OFFICE.

JOHN A. FRASER, OF BERKELEY, CALIFORNIA, ASSIGNOR TO THE KAWNEER COMPANY,
OF NILES, MICHIGAN, A CORPORATION OF MICHIGAN.

WINDOW CONSTRUCTION.

Application filed February 14, 1927. Serial No. 167,903.

The present invention relates to window constructions, and more particularly to the type of windows having sashes that are mechanically operated or actuated.

Among the objects of invention, is to provide a novel window construction having a movable sash or sashes, such as that or those mounted in or on a window frame for swinging movement therein, and means for mechanically operating the same, as also for bringing the sash or sashes into closed and fully closed or stopped position, and also for holding the sash or sashes in moved position, whether in partly opened or fully opened position, or partly closed or fully closed position, or both. The invention is applicable to windows having one or more movable or swinging sashes, and which in the specific illustrated embodiment is disclosed in connection with a three sash window of which the lower sash may be manually operated and the upper two sashes are mechanically operated; the invention also comprehending the application of it to windows having but out movable sash, or but one manually operable sash and with any number, such as two, three or more mechanically operated sashes, or to any number of manually operable sashes with any number, such as one, two or more mechanically movable sashes, or to any number of sashes all mechanically operable, the particular embodiment herein disclosed being by way of illustration only and not by way of limitation.

Another object of the invention is to provide novel means for mechanically operating the sashes such that they may work in unison or simultaneously, and with means for normally limiting the movement of the operating means or sashes, yet so arranged and designed that the sash or sashes may be disconnected from the means for operating it or them whereby the sash or sashes may be readily reversed for cleaning the same or the like as desired. In the specific illustrative embodiment the actuating means comprises a bar or rod slidably carried by the window frame and connected, as by means of a pin and slot device, to the sash such that as the bar is slid, the sash may be caused to swing in or out as the case might be. As a stop means, a removable pin may be so located to limit the movement of the bar and con-

nected parts, but may be removed to permit the further movement of the connected parts, whereby the pin may be removed from the slot of the pin and slot connection between the sash and bar, to free the sash so that it can be reversed for cleaning and other purposes. The bar may have a rack portion and is preferably operated or actuated by a manually operable means, such as a crank and gear device rotatably carried by the window frame, with the crank at a point easily accessible to the person operating the window.

Another feature of the invention is to provide, when operating two or more sashes, means for relatively adjusting the sashes so that they will be even or in the same plane when closed, such adjusting means being effected by providing the crank and gear device with one of the gears loosely rotatable on the shaft of the crank and the other gear rotatably fixed to such shaft so as to positively rotate therewith, such that one rack bar may be moved or slid to operate its respective sash to proper or adjusted relation with respect to the other sash or sashes. Binding means, such as a thrust screw may be then operated to fix the gears to operate in unison for moving the bars simultaneously and hence the sashes connected thereto.

A further feature of the invention is to provide means for holding or locking the sash or sashes in either moved or closed position. In the case of locking the sash or sashes in moved position, this may be effected by having a member so associated with the bar or bars, as the teeth thereof, such that it will normally be out of contact therewith but adapted, by the operating of an easily accessible crank means, to forcibly contact the member with the bar, so as to positively hold it in place and thus prevent movement thereof and the connected sashes by reason of wind pressure or the like, until the member is released from the bar. The member mentioned and the crank means may have cooperating cam means such that as the crank is operated it may cam the member into or out of engagement with the bar or bars.

The invention also comprehends means for bringing the sash or sashes to fully closed position and holding or locking the same in such position, preferably after the

sash has been brought to substantially closed position by the mechanical operating means. This may be effected by providing the sash or sashes with a member having an inclined 5 or cam portion, and a sliding bar having means, such as a member adjustably connected thereto, for engaging such inclined portion or cam, and thus cause a wedging or camming action so as to draw the sash 10 tightly into fully closed or stopped position against the stops of the window frame. By the same means the sash or sashes are held and maintained in locked condition, until the bar be withdrawn and the member or 15 members of the sash or sashes be released. This bar is preferably operated by a manually operable crank means rotatably carried by the window frame and having the manual crank or arm thereof easily accessible to the operator of the window.

Referring to the drawings, Fig. 1 is a vertical, transverse sectional view taken through a window constructed in accordance with the invention;

Fig. 2 is a vertical sectional view taken in a plane represented by a line 2—2 in Fig. 1 of the drawings;

Fig. 3 is a vertical transverse sectional view of the upper part of the window showing the reversibility of a sash;

Fig. 4 is a vertical transverse sectional view of the lower part of the window showing the means for operating the upper sashes including a showing of the lower manually 35 operated sash;

Fig. 5 is a vertical transverse sectional view through a window showing the side thereof with the locking means for holding the window sashes in closed position;

Fig. 6 is a horizontal fragmentary sectional view taken in a plane represented by a line 6—6 in Fig. 1 of the drawings;

Fig. 7 is a horizontal fragmentary sectional view taken in a vertical plane to the 45 operating mechanism at the lower part of the window;

Fig. 8 is a vertical fragmentary sectional view taken in a plane transverse to that of Fig. 7 to the same mechanism;

Fig. 9 is a fragmentary sectional view taken in a plane represented by a line 9—9 in Fig. 7 of the drawings;

Fig. 10 is a fragmentary sectional view taken in a plane represented by a line 10—10 55 in Fig. 1 of the drawings;

Fig. 11 is a fragmentary sectional view taken in a plane represented by a line 11—11 in Fig. 1 of the drawings; and

Fig. 12 is a fragmentary sectional view 60 taken in a plane represented by a line 12—12 in Fig. 5 of the drawings.

Referring now more in detail to the drawings, the invention is shown by way of an illustrative embodiment applied to a window 65 frame having a lintel 1 connected to side

jambs 2 and 3, and a sill 4 carrying a ledge 5. The inner side of the frame may be covered with a molding frame 6.

In the frame are shown a number of window sashes, of which the lower one is manually operated. It comprises side stiles 7, top rail 8 and the lower rail 9, and carries a pane 10. To the side stiles are connected plates 11 to each of which is pivoted at the upper end, a link or supporting arm 12, the latter being pivoted at its lower end through a friction pivot means 13 connected to the side jamb of the window frame. To each side jamb is also connected a plate 14 having a channelled guide flange 15 in the channel of which is adapted to slide a flange 16 of a shoe 17, the latter being pivotally connected by means of a pivot 18 to a projecting end portion 19 of the side plate 11. This construction may be duplicated on the opposite jamb. From this description it will be apparent that the sash may be manually operated by the sash turning about the pivot connection between the links 12 and the side plates 11 and with the shoes 17 sliding with their flanges 16 in the channelled guide flanges 15 of the plates 14, and at the same time the links 12 may turn about the friction pivot devices 13. This sash may be swung from the closed position shown in Fig. 1 to a reverse position shown in Fig. 4, whereby the opposite side of the sash may be accessible for the purpose of cleaning and the like.

Each of the upper sashes are mechanically operated and each comprises side stiles 20, top rails 21 and bottom rails 22, each sash also including a pane 23. To the side stiles 20 are pivotally connected at the upper ends thereof, links 24, the lower ends of which are pivotally connected to plates 25 secured to the side jambs of the window, by any suitable means, such as screws. At the upper corners of the sash, such as at the opposite ends of the top rails 20, are provided 110 guide pins 26 extending into and adapted to slide in metal lined grooves or channels 27 formed in the side jambs 2 and 3 of the window frame. These metal lined channel pieces 27 may have flanges 28, secured, in 115 any suitable manner as by way of screws, to the inner walls of the side jambs.

The top rail 21 of each sash may also have secured to it, in any suitable manner, a bracket or arm 29 extending inwardly and carrying at its inner end a runway pin 30 adapted to slide in a slot 31 provided in a runway member 32 of which the upper runway member is secured to a bar 33, and the lower runway member is secured to a bar 34, both being slidable side by side in a groove or channel 35 provided in side jamb 2 of the window. The bar 33 is longer than the bar 34 inasmuch as the former is designed to operate the upper sash, and the 130

latter the lower sash of those mechanically operated. It will be also noted that the slot 31 in each of the runway members is open at one end so that the pin 32 is adapted, in 5 a given relation, to move out of such slot for the purpose of permitting the reversal of the sash, as in the position thereof in Fig. 3 of the drawings.

It will thus become apparent that when 10 the bars 33 and 34 are moved longitudinally in the channel 35 the runway members 31 will accordingly be moved therewith and by reason of pin and slot connections between them and the brackets 29, will cause the window to swing about the pivotal connections 15 between the links 24 and the stiles 20 thereof as also a swinging of the links about the lower pivotal connections thereof with the plates 25. At the same time the pins 26 in 20 the upper rails will slide in the channels 27. It will be seen from Figure 1, such movement, when the bars 33 and 34 are moved downwardly, will be effected from the dotted line position of the sashes and connected 25 parts to the full line positions thereof, which latter positions are the open positions of the sashes. A reverse movement of the bars will bring the sashes to a close.

When the sashes are closed, they contact 30 on the inner sides thereof against stops 36 carried within the frame of the window, the inner edge of the ledge 5 also forming a part of the stop means for the lower window sash.

35 For the purpose of mechanically causing a sliding movement of the bars 33 and 34 the lower end portions thereof may be provided with rack teeth 38 and 39 in mesh with teeth 40 and 41 of the gears 42 and 43 carried upon a shaft 44 forming a reduced 40 diameter extension of a rotary member 45 rotatably carried in a bearing bracket 46 having feet 47 secured by way of screws 48 or the like to the side jamb 2 of the window 45 frame. The shaft 44 is preferably provided with a flat mill 49 for a part of the length thereof, and the opening in gear 43 is accordingly formed so that the gear 43 will fit on said milled part, and the shaft 44 will 50 be able to positively drive or rotate this gear without danger of slipping. The other gear 42, however, is loosely mounted upon the shaft 44, preferably on the unmilled part thereof. Normally, the gear 42 is made 55 fast so as to rotate in unison with the gear 43 and the shaft 44, by means of a set screw 50 threaded into the end of shaft 44 and having a washer or the like 51 engaging the gear 43. The latter is then pressed against 60 the gear 42 which in turn is forced against a shoulder portion 52 of the rotatable member 45. This will effect a frictional engagement among the parts sufficient to cause the gear 42 to rotate with the gear 43 and shaft 65 44 as a unit. Thus it will be seen that as

the shaft 44 and gears 42 and 43 are rotated, the bars 33 and 34 will be made to slide simultaneously or in unison, and hence likewise cause an opening of the upper sashes.

If the sashes be not in proper relation, such as disposed in a plane, when closed, one sash may be readily adjusted relative to the other to bring them in the proper relation on the same plane when in closed position. 70 This may be effected by loosening the screw 50 to remove the frictional engagement of the gears 43 and 42. The shaft 44 may be turned which will effect a positive turning of gear 43 and sliding of bar 34. The gear 42, being relieved of frictional engagement with the gear 43, will now remain idle, the shaft 44 rotating loosely therein. Hence the bar 33 will also remain idle. When the desired adjustment has been made, the screw 75 50 may be again tightened and the gears locked together as before described, after which these gears will operate in unison.

The member 45 is provided with a socket 53 carrying a cross pin therein 54 adapted to be engaged by the slotted end 55 of a crank 56, the inner end of the crank being capable of fitting loosely in the socket 53, and having at its outer end a handle 57 for manual engagement and operation of the 80 crank. The block 46 may be provided with a recess or socket 58 adapted to receive a thimble 59, the inner end portion 60 of which is adapted to surround a part of the member 45 and extend through an aperture 62 in the molding frame 6, such aperture being in registry with the socket 58, and the outer end of the member 59 being closed except for an aperture through which the shank of the 85 crank 56 passes. The crank is easily removable and replaced so that the slotted end of it may engage with the cross pin 54 and then may be rotated to turn the member 45 and hence the gears 42 and 43 secured thereto. The rotating of these gears will cause 90 a sliding of the racks of the bars and likewise the bars themselves, so as to cause the sashes to open or close, depending upon the direction of rotation of the crank.

It will of course be understood that although two rack bars are shown, that the groove 35 may be of greater width and adapted to permit the sliding therein of more than two rack bars, and in that case the shaft 44 may be of greater length so 100 as to carry a greater number of gears so that they could respectively engage with their respective racks. On the other hand if it be desired, in the illustrated embodiment, to disconnect one rack so that the sash operated by it may not be mechanically operated, but only to operate the other mechanically, the gear driving that rack may be removed from the shaft 54 and a spacer 105 located in its place.

When the sashes are open, and for the purpose of preventing them from closing by reason of the force of the wind or otherwise, holding or locking means may be included to hold or lock the windows in moved position. Such holding or locking means may be effective not only to hold the sashes in open or partly opened condition, but also to hold them in closed or partly closed condition. Such a means, in the illustrated embodiment, comprises one or more sockets 63 which may be of any form, but in the form shown being rectangular in cross section, and forming a part of the block 46. Within the socket 63 may be placed a locking member in the form of a block 64 adapted to slide in the socket 63, and having an end surface 65 thereof adapted to engage with the top of the teeth 38 and 39 of the bars 33 and 34. The block member 64 may also be provided in one of its side faces with a tapered recess 66 acting as a cam surface with which may cooperate the tapered end 67 of a screw 68 threaded into a threaded bore 69 in the block 46. The center line of the screw 68 is located off center of the socket 66, such that when the screw is operated to move the tapered end 67 into the recess 66, it will act as a cam against the cam surface of the socket 65 and cause the block 64 to move inwardly and into engagement with the surface of the teeth, and forcibly bind the same so as to hold the bars 33 and 34 against movement. A reverse movement of the screw 68 will withdraw the tapered cam end 67 from the surface engaged by it in the socket 66 and permit the block 64 to be relieved from the rack teeth of the bars 33 and 34, thus permitting a free movement of the rack bars. The screw 68 extends from the block 46 through a suitable aperture 70 provided in the frame molding 6, and to the projecting end thereof is connected a manually operable handle 71 held secured in rigid connection with the screw by means of a set nut 72 threaded to the outer end of the screw. This handle 71 is located where it is easily accessible to the operator and preferably near the handle 57 which is also easily accessible to the operator. It will thus be seen from the above description that when it is desired to operate the sashes, the handle 71 is operated to unlock the block member 64 from the rack teeth, and then the handle 57 operated to move the sashes to the desired positions, and when so moved, then the handle 71 operated in an opposite direction to turn the screw 68 and cause a camming by way of elements 67 and 66 of the block 64 to forcibly engage the latter with the teeth of the rack bars 33 and 34.

In order that the sashes may be swung to a given angle and no greater, a stop pin 72 may be engaged in the side jamb 2 in a position where it will be hit by the lower runway

member 32, thus bringing the sashes at a stop at the desired angle or open position of the same. This pin 72 is located to stop the movement of the runway member 32 at a point before the pin 30 can move 70 out of the open end of the slot 31 provided in the runway member. One stop pin 72 is sufficient and it is of course understood instead of locating it below the lower runway member, it may be placed in a similar relation below the upper runway member. By reason of the fact that the runway members are connected to the rack bars which are operated by a common means, the limiting of the movement of one of the runway members, will effect the stopping of the whole system including the two bars. The pin 72 preferably extends through an aperture provided in the frame-molding 2 and has a head 73 so that it may be readily engaged, when desired, to withdraw the pin. The purpose of withdrawing the pin is to remove the stopping function, when it is desired to reverse the sashes. It will be apparent that when the stop pin 72 is removed from the position shown in Fig. 1, and that when the bars are operated to a further movement than that limited by the stop pin, the runway members will arrive at a lower position, such that the pins 30 on the sash brackets 29 will pass from and out of the open end of the slots and thus free the sashes whereby the operator may turn them completely around or in reverse position whereby the opposite side of the sash may be accessible 100 for cleaning or other purposes. When bringing the sashes back into place the pins will engage with the upper overhanging portion of the runways above the slots 31 and a racking back of the bars will effect a 105 proper re-engagement of the pins in the slots so that the sashes may then operate mechanically, and then the stop pin 72 may be re-inserted in place.

When the sashes are brought to closed position by the rack bars 33 and 34, they may not close entirely tightly and for the purpose of bringing them tightly into closed position or stopped condition against the stops 36 of the window frame, the lower 115 sash rails 22 may be provided on the opposite side from where the brackets 29 are connected to the sash, with laterally extending arms or bracket members 74 having a tapered projection of finger 75 provided with 120 an inclined or cam surface 76. When the window sashes are brought into substantially closed position, these brackets 74 will be brought into position such as that shown by dotted lines in Fig. 5 of the drawings. Adjacent these and in the jamb 3 is provided a channel or slot 77 in which is adapted to slide a slide bar 78 carrying adjustable members 79 shown more in detail in Fig. 12 of the drawings. These adjustable members 130

79 may be slid along the bar 78 to the desired point and held in adjusted position by set screws 80. The members 79 preferably slide in metal channel pieces 81 fixed into the groove 77. When the bar 78 and the pieces 79 are moved upwardly the latter will engage with the inclined edge or face 76 so as to cause a sort of wedging action or camming thereof and hence bring the sashes into 10 tight engagement with the stop 36 of the window frame, and incidentally will also hold the sashes locked in such position, such that the sashes cannot be opened even by the rack bar and gear mechanism on the 15 side opposite of the window and when the locking means on that side should be released. In other words, the sashes may be locked doubly against unauthorized opening. When the bar 78 is operated in an opposite 20 direction, the members 79 will be moved from the cam surfaces or edges 76 and thus release the bracket members 74 and hence the sashes, so that they may then be operated by the mechanical opening means.

25 The lower end of the bar 78 is provided with a slot 82 in which is adapted to operate a crank pin 83 carried by a crank arm 84 secured to the end of a shaft 85 rotatably supported in a bearing 86 fastened, as by 30 way of screws, or the like, 87 to the inner face of the side jamb 3, as shown in Fig. 5. The shaft 85 extends through an aperture in the frame molding 6 and has secured to the extending end thereof a handle 87 fixed 35 to the end of the shaft by means of a screw 88. As the handle 87 is operated, the shaft 85 will turn with the crank 84 and the crank pin 83, the latter operating in the slot 82 and adapted to move the bar 78 from and to the full 40 line position thereof to the dotted line position thereof in Fig. 12 of the drawings.

While I have herein described and upon the drawings shown an illustrative embodiment of the invention, it is to be understood 45 that the latter is not limited thereto but may comprehend other constructions, details, arrangements of parts, and features without departing from the spirit thereof.

Having thus disclosed the invention, I 50 claim:

I claim:

1. A window construction having a frame, a sash movable in said frame, guide means carried by the frame, means carried by the 55 sash and cooperating with the guide means to be guided by the latter when the sash is moved, supporting means pivotally connected to said frame and to said sash, slid- 60 able means carried by the frame, and means carried by the sash independently of said second mentioned means and connected to said 65 slideable means for moving said sash when the slideable means is moved.
2. A window construction having a frame, 70 a sash movable in said frame, guide means 75 carried by the frame, means carried by the sash independently of said second mentioned means and connected to said slideable means for moving said sash when the slideable means is moved, and means for locking the slideable means in given moved position.
3. A window construction having a frame, a sash movable in said frame, guide means carried by the frame, means carried by the sash and cooperating with the guide means to be guided by the latter when the sash is moved, supporting means pivotally connected to said frame and to said sash, slideable means carried by the frame, means carried by the sash and connected to said slideable means for moving said sash when the slideable means is moved, and manually operative means carried by the frame and engaging said slideable means for moving the same.
4. A window construction having a frame, a sash mounted therein to swing, means carried by the frame and connected to the sash to cause it to swing when said latter means is moved, means for locking said latter movable means in any given moved position, and manually operative means at the inner side of said frame and connected to the slideable means for moving the same.
5. A window construction having a frame, a sash mounted therein to swing, means carried by the frame and connected to the sash to cause it to swing when said latter means is moved, and manually operative means carried by said frame and engaging said movable means for causing it to move in accordance with the operation of the manually operative means.
6. A window construction having a frame, a sash mounted therein to swing, means carried by the frame and connected to the sash to cause it to swing when said latter means is moved, and manually operative means carried by said frame and engaging said movable means for causing it to move in accordance with the operation of the manually operative means, and means for locking said latter movable means in any given moved position.
7. A window construction having a frame, a sash mounted therein to swing, means carried by the frame and connected to the sash to cause it to swing, when said latter means is moved; the connection between said means and said sash comprising a pin and slot device whereby the pin slides in the slot of the device as the sash is swung and said first mentioned means is moved.
8. A window construction having a frame, a sash mounted therein to swing, means car-

- ried by the frame and connected to the sash to cause it to swing when said latter means is moved, said means comprising a rack, and means engaging the rack for causing the same to move.
9. A window construction having a frame, a sash mounted therein to swing, means carried by the frame and connected to the sash to cause it to swing when said latter means is moved, the connection between said means and said sash comprising a pin and slot device whereby the pin slides in the slot of the device as the sash is swung and said first mentioned means is moved, said first mentioned means comprising a rack, and means engaging the rack for causing the same to move.
10. A window construction having a frame, a sash mounted therein to swing, means carried by the frame and connected to the sash to cause it to swing when said latter means is moved, said means having a member provided with a transverse slot, an element carried by said sash and having a pin extending into and movable in said slot when the sash is being swung and said means is moved.
11. A window construction having a frame, a sash mounted therein to swing, a bar slideable in a groove provided in said frame and connected to said sash, said bar having teeth, and means cooperating with said teeth to cause the bar to move to swing said sash.
12. A window construction having a frame, a sash mounted therein to swing, a bar slideable in a groove provided in said frame and connected to said sash, said bar having teeth, and a pinion rotatably carried by said frame and engaging said teeth for causing said bar to move and said sash to swing.
13. A window construction having a frame, a sash mounted therein to swing, a bar slideable in a groove provided in said frame and connected to said sash, said bar having teeth and means cooperating with said teeth to cause the bar to move to swing said sash, and a crank connected to said means for operating the same.
14. A window construction having a frame, a sash mounted therein to swing, a bar slideable in a groove provided in said frame and connected to said sash, said bar having teeth, a pinion rotatably carried by said frame and engaging said teeth for causing said bar to move and said sash to swing, and a manually operable crank connected to said pinion to rotate the same.
15. A window construction having a frame, a plurality of sashes mounted therein to swing, means carried by the frame and connected to the sashes for swinging the same when said means is moved, said means comprising as many movable members as there are sashes to be swung, and a common means for actuating said members in unison.
16. A window construction having a frame, a plurality of sashes mounted therein to swing, means carried by the frame and connected to the sashes for swinging the same when said means is moved, said means comprising as many movable members as there are sashes to be swung, a common means for actuating said members in unison, and means for adjusting the relation of said members to each other whereby the sashes may be opened and closed in correct relation.
17. A window construction having a frame, a plurality of sashes mounted therein to swing, means carried by the frame and connected to the sashes for swinging the same when said means is moved, said means comprising as many movable members as there are sashes to be swung, a common means for actuating said members in unison, and means associated with said members for holding the same in moved position.
18. A window construction having a frame, a plurality of sashes mounted therein to swing, means carried by the frame and connected to the sashes for swinging the same when said means is moved, said means comprising as many slideable bars as there are sashes to be swung, and a common means for sliding said bars in unison.
19. A window construction having a frame, a plurality of sashes mounted therein to swing, means carried by the frame and connected to the sashes for swinging the same when said means is moved, said means comprising as many slideable bars as there are sashes to be swung, a common means for sliding said bars in unison, and locking means adapted to engage a bar for holding the bars in moved position.
20. A window construction having a frame, a plurality of sashes mounted therein to swing, means carried by the frame and connected to the sashes for swinging the same when said means is moved, said means comprising as many slideable bars as there are sashes to be swung, a common means for sliding said bars in unison, and locking means adapted to engage a bar for holding the bars in moved position, said locking means comprising an element normally out of engagement with said bar, and cam means adapted to cause the element to forcibly engage the bar to effect the locking action.
21. A window construction having a frame, a plurality of sashes mounted therein to swing, means carried by the frame and connected to the sashes for swinging the same when said means is moved, said means comprising as many slideable bars as there are sashes to be swung, said bars having rack portions, and means engaging said rack portions for actuating said bars.
22. A window construction having a frame, a plurality of sashes mounted therein

to swing, means carried by the frame and connected to the sashes for swinging the same when said means is moved, said means comprising as many slidable bars as there are 5 sashes to be swung, said bars having rack portions, pinions meshing with said racks, and manually operable means for rotating the pinions in unison to actuate the bars.

23. A window construction having a 10 frame, a plurality of sashes mounted therein to swing, means carried by the frame and connected to the sashes for swinging the same when said means is moved, said means comprising as many slidable bars as there 15 are sashes to be swung, said bars having rack portions, pinion means engaging said rack portions for actuating said bars, and means cooperating with said rack portions for locking the bars in moved position.

24. A window construction having a 20 frame, a plurality of sashes mounted therein to swing, means carried by the frame and connected to the sashes for swinging the same when said means is moved, said means 25 comprising as many slidable bars as there are sashes to be swung, said bars having rack portions, pinion means engaging said rack portions for actuating said bars, and means cooperating with said rack portions for locking 30 the bars in moved position, said locking means comprising an element normally out of engagement with said rack portions, and means for causing said element to forcibly engage said rack portions for locking the 35 same in moved position.

25. A window construction having a 40 frame, a plurality of sashes mounted therein to swing, means carried by the frame and connected to the sashes for swinging the same when said means is moved, said means comprising as many slidable bars as there 45 are sashes to be swung, said bars having rack portions, pinion means engaging said rack portions for actuating said bars, and means cooperating with said rack portions for locking the bars in moved position, said locking means comprising an element normally out of engagement with said rack portions, said element having a cam portion, and means 50 having a cam portion engaging the cam portion of said element for causing said element to forcibly engage said rack portion to lock the bars in moved position.

26. A window construction having a 55 frame, a sash mounted therein to swing, means carried by the frame and connected to the sash to cause the sash to swing when said means is moved, and means cooperating with the first mentioned means for limiting 60 the movement thereof at a given swung position of the sash.

27. A window construction having a 65 frame, a sash mounted therein to swing, means carried by the frame and connected to the sash to cause the sash to swing when

said means is moved, a removable stop element located to limit the movement of said first mentioned means, the connection between said latter means and said sash being arranged to permit disconnection of the sash 70 from said first mentioned means when said stop element is removed for reversibility of said sash.

28. A window construction having a 75 frame, a sash mounted therein to swing, means carried by the frame and connected to the sash to cause the sash to swing when said means is moved, said means having a member with an open ended slot, said sash having an element extending into said slot 80 and slidably therein, a removable stop member normally limiting the movement of said means and slotted member but when removed permitting further movement of the means and sash whereby the element carried 85 by the sash may be moved from said slot through the open end thereof to permit reversing of the sash.

29. A window construction having a 90 frame, a sash mounted therein to swing, means carried by the frame and connected to the sash to cause the sash to swing when said means is moved, said means having a member provided with a transverse slot open at one end thereof, a pin carried by the sash 95 and normally movable in said slot, a removable stop element carried by the frame and adapted to be engaged by said slotted member to normally limit the movement thereof and said means, said means being removable 100 to permit further movement of the slotted member and the movement of the pin from said slot through the open end thereof for permitting reversing of the sash.

30. A window construction having a 105 frame, a sash mounted therein to swing, means carried by the frame and connected to the sash to cause the sash to swing when said means is moved, and movable means carried by the frame and adapted to engage with the sash for moving the sash into fully closed position and to hold the sash locked in said closed position.

31. A window construction having a 110 frame, a sash mounted therein to swing, means carried by the frame and connected to the sash to cause the sash to swing when said means is moved, a member carried by said sash and having an inclined portion and a movable means carried by the frame and engageable with the inclined portion of said member for bringing the sash into fully closed position and for holding the sash locked in said closed position.

32. A window construction having a 115 frame, a sash mounted therein to swing, means carried by the frame and connected to the sash to cause the sash to swing when said means is moved, a member carried by said sash and having an inclined portion, 120

and a slide bar slidably carried by said frame and means carried by the bar for engaging the inclined portion of said member for moving the sash to fully closed position and for holding said sash in said closed position.

33. A window construction having a frame, a sash mounted therein to swing, means carried by the frame and connected to the sash to cause the sash to swing when said means is moved, a member carried by said sash and having an inclined portion, a slide bar slidably carried by said frame and means carried by the bar for engaging the inclined portion of said member for moving the sash to fully closed position and for holding said sash in said closed position, and manually operable means cooperable with said bar for actuating the same.

34. A window construction having a frame, a sash mounted therein to swing, means carried by the frame and connected to the sash to cause the sash to swing when said means is moved, a member carried by said sash and having an inclined portion, a slide bar slidably carried by said frame, an element adjustably connected to said bar and adapted to engage said inclined portion of said member, and means for actuating the bar.

35. A window construction having a frame, a sash mounted therein to swing, means carried by the frame and connected to the sash to cause the sash to swing when said means is moved, a member carried by said

sash and having an inclined portion, a slide bar slidably carried by said frame, a crank means rotatably carried by said frame and engaging said bar to actuate the same, said bar having means adapted to engage the inclined portion of said members.

36. A window construction having a frame, a sash mounted therein, to swing, means carried by the frame and connected to the sash to cause the sash to swing when said means is moved, a member carried by said sash and having an inclined portion, a slide bar slidably carried by said frame, said bar having a slot therein, crank means having a pin extending into the slot in said bar and adapted to actuate said bar, said bar having means adapted to engage the inclined portion of said member.

37. A window construction having a frame, a sash mounted therein, to swing, means carried by the frame and connected to the sash to cause the sash to swing when said means is moved, a member carried by said sash and having an inclined portion, a slide bar slidably carried by said frame, an element adjustably connected to said bar and adapted to engage said inclined portion of said member, said bar having a slot therein, crank means having a pin extending into the slot in said bar and adapted to actuate said bar, and manually operable means connected to the crank for operating the same.

In witness whereof, I hereunto subscribe my name to this specification.

JOHN A. FRASER.
